UNITED STATES PATENT OFFICE.

WILLIAM A. HANDLEY, OF ARLINGTON, WASHINGTON.

DESIGN FOR A STAND FOR SAWING-MACHINES.

SPECIFICATION forming part of Design No. 33,529, dated November 6, 1900.

Application filed October 8, 1900. Serial No. 32,452. Term of patent 7 years.

To all whom it may concern:

Be it known that I, WILLIAM A. HANDLEY, a citizen of the United States, residing at Arlington, in the county of Snohomish and State of Washington, have invented and produced a new and original Design for a Stand for Sawing-Machines, of which the following is a specification.

The invention relates to a new and original design for a stand for a sawing-machine; and it has for its object to provide a design of this character which will be both convenient and useful.

The leading feature of the design consists in the design forming the subject-matter of the accompanying illustration.

In the drawings, Figure 1 is a perspective view of a stand, showing my new and original design. Fig. 2 is a side elevation. Fig. 3 is a front elevation.

Referring to the drawings, 1 designates a stand composed of sides 2 and 3, connected at an intermediate point by a transverse piece 4, tapering from its ends to its center and provided with opposite triangular openings 5. The side 2, which has a tapering rear portion, is provided with a projecting front portion and is composed of a horizontal base 6, a front post 7, and an inclined brace 8, extending downward from the top of the post to the rear end of the base and having an enlargement at its lower end. The base, the post, and the brace form an opening 9, which tapers toward the top of the stand. The post 7 is provided

with a forwardly-extending arm 10, provided at its top with an approximately triangular enlargement 11, and it extends forward from the top of the stand and has an inclined lower front edge 12, extending downward and rearward to the base and presenting a concave 40 face. The approximately triangular enlargement 11 is disposed longitudinally of the side 2.

The side 3, which tapers rearwardly, is composed of a base 13, a brace 14, and a post 15, having a forwardly-projecting arm extended laterally at its outer portion beyond the plane of the body portion of the side, as clearly illustrated in Fig. 3 of the accompanying drawings. The arm is provided at its top with an approximately triangular enlargement 16, which is deflected laterally to conform to the configuration of the arm 17. The base is provided at its inner side with a segmental extension 18. The configuration of the side 3 is otherwise approximately the same as the side 2.

What I claim is—

The design for a stand herein shown and described.

In testimony that I claim the foregoing as my own I have hereto affixed my signature in the presence of two witnesses.

WILLIAM A. HANDLEY.
